VAPOR TRAP

William S. Goff, Cleveland, Ohio, assignor to The Clark Manufacturing Company, Cleveland, Ohio, a corporation of Ohio

Application November 8, 1949, Serial No. 126,227

26 Claims. (Cl. 137—185)

1

This invention relates to fluid traps such as steam traps, and particularly to valve mechanism of both the submersible and non-submerging float types for opening and closing a discharge orifice.

Heretofore a number of problems involved in the construction and mode of operation of valve mechanisms for vapor traps have been only partially solved by effecting compromises between a number of desirable conditions. As a result, most of these desirable conditions have not been met in an entirely satisfactory manner. The most important of these desirable conditions are:

- (a) Positive actuation of the discharge valve under all conditions encountered in service;
- (b) High sensitivity to changes in the conditions calling for opening and closing of the discharge valve;
- (c) Efficient removal of non-condensable gases;
- (d) Operability of a given trap over a wide range of fluid pressures and condensate discharge rates;
- (e) Adaptability of a given trap size and design to still wider ranges of operating pressures and condensate discharge rates with minimum changing of parts;
- (f) Ruggedness and durability in service;
- (g) Compactness of the valve actuating mechanism;
- (h) Simplicity and economy of manufacture and repair.

The difficulties encountered in satisfying all of these conditions as fully as possible are principally due to friction in the mechanism, to the large initial force required to crack the valve open against the internal pressure in the trap, and to the amplitude of valve travel required during the remainder of the opening operation to permit discharge of condensate through the discharge orifice with minimum throttling and turbulence.

A measure of success in overcoming these difficulties has been achieved in the prior art by employing two successively operative fulcrums on the float-actuated valve lever. This has involved pivoting the lever about a first or primary fulcrum disposed close to the valve until the valve is cracked open sufficiently to overcome the great initial resistance to its opening movement, and then pivoting the lever about a secondary fulcrum further removed from the valve to obtain the desired total amplitude of valve travel to its fully open position.

An application of the dual fulcrum principle is shown in U. S. Patent No. 2,004,953 to Kaye. The mechanism of this patent is of a relatively

2

simple character. However, the geometry of the lever system is such that either the valve travel while the primary fulcrum is operative is too small to carry the valve out of the region in which a large opening force is required, or the initial mechanical advantage is too small to effect reliable operation. For this mechanism to be reliably operative over a wide range of steam pressures for opening a large valve capable of handling large condensate discharge rates, an undesirably large housing containing a long valve lever is required.

The present invention is an improvement over these and other prior art devices employing the dual fulcrum, or differential lever, principle.

A main object of the invention is to provide a dual fulcrum actuating mechanism for moving a large spherical valve element between open and closed positions in high pressure systems without enlarging the lever and trap housing beyond sizes formerly operative only at lower pressures and lower rates of condensate discharge.

Another object of the invention is to provide such a dual fulcrum actuating mechanism that is small and compact, yet capable of functioning efficiently over a wide range of vapor pressures and condensate discharge rates.

Another and more specific object of the invention is to provide a dual fulcrum actuating mechanism which will delay the valve opening operation until the float has moved a substantial distance and has developed close to its maximum power.

Another specific object of the invention is to provide an improved variable vent for an inverted bucket type of valve actuating float for increasing the power derivable from a float of a given size during its downward movement, thereby more completely achieving the above enumerated desirable conditions.

Other objects and advantages of the invention will become apparent from the following description of illustrative embodiments thereof, taken in conjunction with the accompanying drawings in which:

Figure 1 is a side elevation of a vapor trap embodying the invention, a portion of the housing being broken away to show the valve mechanism with the valve fully closed and the inverted bucket in its fully raised position;

Figure 2 is a fragmentary vertical section on an enlarged scale showing the valve still in its fully closed position after the bucket has started its downward travel;

Figure 3 is a fragmentary vertical section, similar to Fig. 2, showing the valve, the valve lever,

and a portion of the bucket after they have moved to positions for first cracking the valve open;

Figure 4 is another fragmentary vertical section similar to Fig. 2, showing the valve and valve lever just as the second of the two fulcrums becomes operative during the opening of the valve, a fourth position with the valve in a substantially fully open condition being shown in phantom outline;

Figure 5 is a fragmentary vertical section on an enlarged scale showing the connection between the bucket and the valve lever that provides a variable vent for the bucket, the plane of the section being indicated by the line 5—5 in Fig. 3 but the variable vent being shown in its closed position;

Figure 6 is a bottom view of the bucket and illustrates details of the connection between the bucket and the valve lever;

Figure 7 is a fragmentary vertical section through the valve, the plane of the section being indicated by the line 7—7 in Fig. 3;

Figure 8 is another fragmentary vertical section through the valve, the plane of the section being the same as in Fig. 7 but the valve lever being shown in a position for removing it from the associated parts of the valve mechanism;

Figure 9 is a perspective view of a yoke in which the valve lever is mounted and which provides bearing surfaces for fulcrum edges on the valve lever;

Figure 10 is another fragmentary vertical section similar to Fig. 2, but showing how positive closing of the valve is assured under all conditions of operation; and

Figure 11 is a vertical section through the center of a modified form of the invention in which the invention is applied to a vapor trap of the open bucket type.

Referring to Figs. 1 to 10, the invention is shown as applied to a steam trap having a cup-shaped body or housing 1 including a separable cover member 2 secured to the body 1 by means of bolts 3 to provide a condensate chamber 4. The chamber 4, which is normally full of liquid, is provided with a steam and condensate inlet 5 at the bottom thereof, and the cover 2 defines an opening 6 through which condensate and accumulated gases may be discharged.

In side the chamber 4, the cover member 2 is provided with a counterbore 7 concentric with the discharge opening 6 and of greater diameter for receiving the upper end of a valve port housing 8. A gasket 9 is disposed between the upper end of the valve port housing 8 and the upper end of the counterbore 7, and an outwardly flanged orifice sleeve 10, defining a circular valve seat 11, is inserted into the valve port housing with a press fit. The valve port housing 8 is secured to the cover member 2 by means of a plurality of bolts 12 (Fig. 7).

A yoke 15, having a pair of downwardly extending arms 16 and 17 and an aperture 18 through the base thereof, is secured to the valve port housing 8 with the orifice sleeve 10 passing through the aperture 18, the yoke being firmly held in place by a flange on the orifice sleeve.

One of the arms 16 of the yoke 15 has an irregularly shaped aperture 20 therethrough, and the other arm 17 has a similar aperture 21 therethrough, a slot 22 being cut from the lower end of the arm 17 into the aperture 21 for a purpose hereinafter described.

A movable valve element 23, having a spheri-

cal surface 24, is normally seated against the valve seat 11 when closed, being held against the valve seat in a manner hereinafter described. A valve actuating lever 25, having a pair of laterally extending trunnions 26 and 27, is mounted with the trunnions respectively projecting outwardly into the apertures 20 and 21 in the arms of the yoke 15. The valve element 23 is provided with a cylindrical extension or stem 28 that projects through an aperture in the lever 25, and the valve element is firmly secured to the lever by any suitable means, such as deformable lock nut 29, or the like.

The generally horizontal upper edges of the apertures 20 and 21 in the arms of the yoke 15 are similarly formed so that each provides two bearing surfaces 30 and 31 for fulcrum edges formed on the trunnions of the valve actuating lever 25. As most clearly shown in Figs. 2 to 4, one edge of each of the trunnions 26 and 27 is upwardly turned to provide a pair of transversely extending and aligned fulcrum edges 32. The adjacent terminal edge of the valve lever 25 constitutes a second pair of aligned fulcrum edges 33 which extend transversely of the lever 25. In the course of movement of the valve lever 25, as hereinafter described, the primary fulcrum edges 32 respectively engage the two bearing surfaces 30 and cause the valve element 23 to be moved away from the valve seat 11. As the valve lever is further rotated in the same direction, the secondary fulcrum edges 33 respectively engage the two bearing surfaces 31; and the primary fulcrum edges 32 are respectively disengaged from the bearing surfaces 30 as the lever is rotated on the secondary fulcrum edges to move the valve element further away from the valve seat.

As is most clearly shown in Fig. 3, the primary fulcrum edges 32 lie in a diametrical plane A—A of the spherical valve surface 24. As is illustrated by the sequence of positions shown in Figs. 2 to 4, this diametrical plane becomes substantially parallel to the valve seat 11 as the primary fulcrum edges 32 first engage their bearing surfaces 30 for initially moving the valve element away from the valve seat. This parallel relationship between the two planes theoretically should exist when the lever has pivoted through half of the angle through which it is supported on the primary fulcrums. However, the relationship shown approximates this ideal condition sufficiently closely for all practical purposes and is most convenient to construct.

With this relationship between the primary fulcrum edges 32 and the spherical surface 24 of the valve element, the initial direction of movement of the spherical center of the valve element is in a direction normal to the plane of the valve seat, thus effecting substantially the maximum effective opening of the valve for a given angle of rotation of the valve lever. This relationship also insures that the downward direction pull of the bucket on the lever 25 will be approximately normal to the lever arm at this time when the most effective application of that pull is needed.

The primary fulcrum edges 32 are preferably located on a line closer to the center of the spherical valve surface 24 than the spherical surface itself (i. e. on a line that passes between a portion of the spherical surface and its center) in order to obtain sufficient mechanical advantage from the lever to overcome the high resistance to initial movement of the valve element from the valve seat. As the valve element moves

away from the valve seat, thereby permitting the escape of accumulated gases and condensate through the orifice at a progressively increasing rate, the pressure difference on the high and low pressure surfaces of the valve element is reduced in accordance with the diminishing fluid velocity over the low pressure valve surface and a constantly diminishing force is required to continue the opening movement of the valve element.

It is desirable that the valve element be moved from its fully closed position to its fully open position with a minimum angular rotation of the valve lever 25, and a substantial increase in the movement of the valve element per degree of angular travel of the lever results when the secondary fulcrum edges 33 contact the bearing surfaces 31 to provide a longer lever arm between the point of rotation of the valve lever and the center of the valve element. This shifting of the center of rotation of the valve lever is accompanied, of course, by a reduction in the mechanical advantage of the lever, which is permissible after the resultant force urging the valve element toward the valve seat has also been substantially reduced as explained above.

The opposite end of the valve lever 25 from the secondary fulcrum edges 33 is deformed to provide a generally cylindrical socket 35 to which an inverted bucket is pivotally attached by means of a connecting device 36. The connecting device 36 comprises a spindle having a hemispherical upper end 37, a cylindrical neck 38 of reduced diameter, and an enlarged portion 39 which is rounded at its lower edge and terminates in a stem 40 having a circumferential groove 41 adjacent its lower end. The socket end of the lever 25 is bifurcated to provide a longitudinally extending slot 42 that accommodates the neck 38 of the connecting device with the hemispherical upper end thereof disposed within the socket 35. The connector is thus suspended from the socket 35 of the lever 25 in a manner permitting free swinging movement of the connecting device about an axis parallel to the cylindrical axis of the socket.

The bucket 45 comprises a cylindrical shell having an open lower end and a closed top 46 that is preferably dome-shaped. The top 46 of the bucket has a circular depression 47 formed therein and an aperture 48 through the bottom of the depression. The aperture 48 is adapted to loosely receive the stem 40 of the connector 36, and the surface contour of the depression 47 conforms to the rounded lower edge surface of the connector portion 39 so that an effective gas seal is produced when the two surfaces are firmly engaged.

A yieldable member, such as a thin leaf spring 49 that is normally bowed from end to end as shown in Fig. 10, is disposed inside the bucket, and the stem 40 of the connector projects through an aperture in the center of the spring. A generally U-shaped bracket 50 is disposed to straddle the spring 49 with its legs upturned to engage the top 46 of the bucket and limit upward movement of the connector 36. The stem 40 of the connector also projects through an aperture in the center of the bracket 50, and a deformable lock nut 51 engages the groove 41 of the stem of the connector for preventing downward movement of the spring and the bracket with respect to the connector. Thus, the ends of the spring 49 bear upwardly against the top of the bucket and urge the connector downwardly with respect to the bucket and into seating engagement

with the surface of the depression 47. Upward movement of the connector with respect to the bucket is yieldingly resisted by the spring and positively limited by the bracket 50, as shown in Fig. 5. The stiffness of the spring is selected so that the weight of the bucket, when suspended in the liquid in the trap and substantially filled with the liquid, is more than sufficient to straighten the spring and hold the parts in the relative positions shown in Figs. 2 and 3. When the downward pull of the bucket is very small due to the accumulation of vapor therein, however, the spring should hold the connector in seating engagement with the surface of the depression 47, as shown in Figs. 1, 5 and 10 and further described hereinafter.

The aperture 48 through the top of the bucket is substantially greater in diameter than the diameter of the stem 40 of the connector so as to provide an auxiliary vent of considerable cross-sectional area for exhausting vapor from the bucket when the connector is raised with respect to the bucket. When the connector is seated in the depression 47 in the top of the bucket, this auxiliary vent is closed. A smaller vent opening 52 in the top of the bucket remains open at all times, however, in accordance with conventional practice. The weight of the bucket may be adjusted to balance the mechanism by mounting a steel ring 54 of appropriate size inside the bucket adjacent the lower end thereof.

The leaf spring 49, restraining opening of the auxiliary vent 48, also serves to restrain the bucket from swinging from side to side about the connector 36 and causes the bucket and connector to swing together as a unit about the socket 35.

When assembling the valve actuating mechanism contained within the chamber 4, the valve lever 25, with the valve element 23 secured thereto, is held in vertical alignment with the slot 22 in the yoke arm 17 and in the laterally off-center position with respect to the arms 16 and 17 illustrated in phantom outline in Fig. 8. The lever 25 is then moved vertically into the position shown in solid lines in Fig. 8, and then horizontally to the left to move the trunnion 26 into the aperture 20 in the yoke arm 16. The free end of the lever 25 is then rotated to bring the valve element 23 into position to close the valve seat 11.

When initially installing the trap in vapor system, the trap is preferably primed so that the chamber 4 is full of liquid. When the trap cover 2 is put in place with the bucket and valve mechanism attached thereto, the bucket will drop to the bottom of the trap, and the valve mechanism will assume the position illustrated with solid lines in Fig. 10. When the vapor system is turned on and vapor begins to bubble through the inlet 5, the vapor accumulates in the bucket at a faster rate than it can escape through the small vent 52, thus causing the bucket to become buoyant and rise to the top of chamber 4, where it comes to rest as shown in Fig. 1 with the auxiliary vent 48 closed.

As shown in Figs. 9 and 10 the apertures 20 and 21 in the legs of the valve supporting bracket 15 are shaped to permit the valve to fall open when there is no pressure in the trap and the bucket is in its lowermost position. Downward falling of the valve element and the adjacent end of the valve lever are limited by the lower edges of the apertures 20 and 21 upon which the trunnions 26 and 27 respectively rest. The lower edge of each of the apertures 20 and 21 is shaped to provide

trunnion supporting surfaces at two different levels. The uppermost of these surfaces 53 is adapted to support the adjacent end of the lever 25 during upward movement of the bucket, and the lever trunnions 26 and 27 pivot on these surfaces to raise the valve element 23 into seating engagement with the valve seat 11. Thus, when vapor has bubbled into the trap in sufficient quantity to raise the bucket, the valve will close before the vapor pressure has risen to a point sufficient to blow through the open exhaust valve. When the pressure in the vapor system has reached its normal operating range, this pressure alone is sufficient to hold the valve element against the valve seat and support the weight of the valve element and the adjacent end of the lever. Upward movement of the bucket and upward swinging of the valve lever are limited by the valve element bearing against its seat and by the trunnions 26 and 27 bearing in the opposite direction against the supporting surfaces 53, as shown in phantom outline in Fig. 10. This is the relationship between the various parts of the mechanism that exists each time the valve is completely closed during normal operation and is the same relationship illustrated on a smaller scale in Fig. 1.

To meet different conditions of operating pressure and volume of condensate that may be handled within the limits imposed by the size of the trap housing, only the valve element 23 and the orifice sleeve 10 need be changed. By appropriately proportioning the dimensions of the different sizes of valve elements and orifice sleeves, the above described relationship between the center of the spherical surface of each valve element and the position of the primary fulcrums may be maintained. The ready removability of the valve lever from the bracket 15 in which it is supported and the simple manner in which the valve element is secured to the valve lever make the substitution of different sizes of valve elements a simple operation. The substitution of different sizes of orifice sleeves is obviously equally simple, and the entire operation may be quickly performed. Thus, a minimum number of replacement parts need be purchased for converting a trap to operate over different pressure ranges. The adaptability of a given trap for operation over different pressure ranges by merely substituting two easily exchangeable parts also keeps to a minimum the number of different trap sizes that must be manufactured and stocked by the trap supplier.

The cycle of operation of this form of trap will be described as applied to the elimination of condensate and accumulated gases from a steam system, starting with the bucket 45 in its uppermost position and with the valve element 23 closing the discharge orifice 11, as shown in Fig. 1. The chamber 4 is always substantially full of water, but the water level inside the float varies over a considerable range. Under the conditions illustrated in Fig. 1, the water level inside the bucket may be approximately at the level indicated by the line B—B, the space above the water level inside the bucket being occupied by steam and accumulated gases. At this point in the cycle, the bucket is in its most buoyant condition and bears upwardly against the connector 36 holding the connector portion 39 upwardly against the bottom of the lever socket 35. Only the small vent 52 is open and the escape of gases from the bucket through this vent is relatively slow. At this stage, all of the fulcrum edges are spaced from their bearing surfaces, a condition which

remains unchanged during opening of the auxiliary vent 48, as most clearly shown in Fig. 1.

In due course, by reason of the escape of gases from the small vent 52 and the condensation of steam above the water level in the bucket, the water level rises inside the bucket, causing it to lose buoyancy and start to sink. The first small downward movement of the bucket takes up the lost motion slack between the connector 36 and the socket 35 of the valve lever, without moving the valve lever, until the connecting device is suspended from the socket 35 by the hemispherical portion 37 and the bucket is suspended from and partially supported by the connector. This opens the auxiliary bucket vent to the maximum effective cross-section determined by the size of the aperture 48, thus allowing a more rapid escape of steam and gases through the vent and rapid reduction of the buoyancy of the bucket. Up to this point, movement of the valve lever is restrained by friction between the valve element and valve seat. The positions of the bucket and connector at this stage are also shown in Fig. 2.

After the loss of buoyancy of the bucket has increased its downward pull on the lever 25 to a point sufficient to overcome the friction between the valve element 23 and its seat 11 the valve element rotates on its seat in a counter-clockwise direction as viewed in Fig. 2. This rotation brings the primary fulcrum edges 32 into contact with the bearing surfaces 30 as shown in Fig. 3, whereupon further downward movement of the bucket causes the lever to pivot on the fulcrum edges 32 for initially moving the valve element substantially vertically away from its seat. By the time this initial cracking of the valve occurs, the bucket has had an opportunity to vent most of the gases contained therein through the small vent 52 and auxiliary vent 48 and has attained close to its maximum power. The downward pull of the bucket for pivoting the lever about the primary fulcrum edges 32 for initially cracking the valve open is thus greatly increased compared to the downward pull at the beginning of the cycle. In traps where the initial movement of the bucket is opposed by the full force required to crack the valve open, either a longer lever or a larger bucket, or both, are required under given conditions of operation.

When downward movement of the bucket has pivoted the valve lever about the primary fulcrum edges 32 to the position shown in Fig. 4, the secondary fulcrum edges 33 contact their bearing surfaces 31. Further downward movement of the bucket and rotation of the valve lever then causes the lever to pivot about the secondary fulcrum edges 33 until the bucket contacts the bottom of the trap housing, at which point the valve is fully open. This position of the lever is illustrated in phantom outline in Fig. 4.

When the valve lever first cracks the valve open, the water and accumulated gases in the chamber 4 begin to flow out through the orifice 11, and this reduces the pressure differential between the high and low pressure sides of the valve element. However, due to the velocity effect of the water and gases passing through the valve orifice while only partially open, the valve element maintains substantially the same high resistance to movement away from its seat during a substantial portion of the movement of the valve lever on the primary fulcrum edges. By the time the secondary fulcrum edges contact their supporting surfaces 31, this velocity effect is greatly reduced, and completion of the valve opening

movement of the lever requires a constantly diminishing downward pull by the bucket. Accordingly, the last stage of the opening movement is reliably carried out in spite of the reduced mechanical advantage resulting from shifting the axis of rotation from the primary to the secondary fulcrum edges. This last stage of opening movement of the valve element 23 is also opposed by a constantly diminishing differential between its high and low pressure sides, and little or no downward pull by the bucket is necessary to hold the valve in its fully opened position. As a result, the socket 35 of the valve lever will generally come to rest upon the top of the cylindrical portion 39 of the bucket connector 36, as shown in Fig. 10, though the secondary fulcrum edges 33 may remain in contact with their bearing surfaces 31.

As water and accumulated gases flow out through the open orifice 41, some additional gases flow from the inlet 5 into the inverted bucket. However, since the gases above the water level in the bucket are being exhausted at a relatively rapid rate during downward movement of the bucket, sinking of the bucket to the bottom of the trap is assured. When the bucket has come to a stop at the bottom of the trap, however, the auxiliary vent 48 closes and further escape of gases from the bucket can take place only at relatively slow rate through the small vent 52.

When the flow of condensate through the trap has substantially reduced the distance to which liquid is backed up in the inlet line 5, steam will begin to bubble into the trap through the inlet 5 at an increased rate and will collect in the upper part of the bucket much faster than it can be discharged through the small vent 52. As a result, the water level in the bucket is rapidly forced downwardly by accumulation of gases in the upper part of the bucket, and the bucket rapidly regains buoyancy and begins to rise and return the valve element to its closed position.

At the beginning of the valve-closing operation the pressure differential between the high and low pressure sides of the valve element may or may not be sufficient to hold the secondary fulcrum edges 33 against their bearing surfaces 31. Thus, the closing movement of the valve lever may initially involve either pivotal movement about the secondary fulcrum edges 33 or pivotal movement of the trunnions 26 and 27 on the supporting surfaces 33, described above. In any event, as the bucket rises and causes the valve lever to rotate in a clockwise direction as viewed in Figs. 1 to 4, the valve element will be raised into contact with the valve seat, at which point the pressure differential between the high and low pressure sides of the valve element will insure centering of the valve element on its seat and tight closing of the valve.

During the final movement of the valve element toward the valve seat, the primary fulcrum edges 32 will normally be in engagement with their supporting surfaces 33, and the various parts of the mechanism will again reach the condition shown in Fig. 3, except that the auxiliary vent 48 will be closed due to the buoyancy of the bucket. At this point, the buoyancy of the bucket is sufficient to continue the clockwise rotation of the lever from the position shown in Fig. 3 to the position shown in Figs. 1 and 2 by rotating the valve element upon its seat, thus returning the mechanism to the starting position shown in Fig. 1 and completing the cycle of operation.

Some of the details of the cycle of operation

described above cannot readily be visually observed, even while using a transparent glass housing 1, because of the rapid movement of the valve mechanism. The entire cycle of operation 5 may be completed in a fraction of a second or 10 may require several seconds, but any substantial amount of time during which the parts remain stationary for easy observation occurs either with the bucket at rest in its uppermost position or 15 at rest in its lowermost position. As a result, some of the details of the cycle of operation described above are somewhat conjectural under some conditions of operation. However, the improved overall operation resulting from the 20 critical features of the invention (such as the valve and fulcrum relationship, the variable vent and lost motion connector, and the delay of the opening of the valve until the bucket has acquired close to its maximum power) can only be 25 explained if the cycle of operation takes place substantially as described in all of its essential details. Regardless of the accuracy of my theory of operation of the device, the advantages of the invention are evidenced by substantially improved overall operation, and I do not wish the invention to be limited by any particular theory of operation beyond what is required by the appended claims.

A valuable characteristic of the valve mechanism described above is its suitability for use in traps other than those of the inverted bucket type such as the open or upright bucket and closed float types. The adaptability of the mechanism is illustrated in Fig. 11 by its application to an open bucket type of trap. In Fig. 11, parts identical or substantially identical with those in the trap of Figs. 1 to 10 are identified by the same reference characters employed in Figs. 1 to 10.

Referring to Fig. 11, the trap comprises a cup-shaped body or housing 61 and a separable cover member 62 that are generally similar to those shown in Fig. 1, and a spacing element 63 therebetween. The spacing element 63 includes a partition 64 that divides the interior of the housing 61 into a lower condensate collecting chamber 66 and an upper chamber 67 containing the valve mechanism proper. The housing 61, cover member 62, and spacing element 63 are separated by gaskets 68 and 69, and the three parts of the housing are firmly secured together at their flanges in a well known manner by suitable bolts (not shown).

The lower condensate chamber 66 is provided with a steam and condensate inlet 71 disposed in the side wall of the spacing element 63, and the cover member 62 defines an opening 6 through which condensate is discharged. Inside the upper chamber 67, the cover member 62 is provided with a counterbore 7 concentric with the discharge opening 6 and of greater diameter for receiving the upper end of a valve port housing 8. The valve port housing is mounted in the counterbore 7 of the cover member 62 in the same manner as in the embodiment of the invention shown in Figs. 1 to 10. The valve port housing 8 in Fig. 11 carries a valve seat, valve element, valve lever, and associated supporting structure, all of which are identical with the corresponding parts in Figs. 1 to 10. Further description of these parts is, therefore, not required.

A float 72 of the open bucket type is disposed within the lower condensate chamber 66 and comprises a cup-shaped upper portion 73 having a cup-shaped well 74 of substantially smaller diameter extending downwardly from the upper

portion and centrally disposed with respect thereto.

A connecting device for attaching the float to the valve lever 25 consists of a generally vertical disposed connecting rod 75 that passes through an aperture 76 in the partition 64. The rod 75 has a reduced neck portion 77 adjacent its upper end and terminates in an enlarged hemispherical portion 78. The neck portion 77 fits in the slot 42 in the bifurcated end of the lever 25, and the hemispherical portion 78 is disposed within the lever socket 35. The lower end of the connecting rod 75 terminates in a threaded portion of reduced diameter that passes centrally through the bottom of the float well 74 and is secured thereto as by a nut 81. A suitable washer 82 and gasket 83 are preferably mounted on the threaded portion of the connecting rod 75 above the bottom of the float well 74 for sealing the well against leakage where the connecting rod passes therethrough.

A tube 84 is threaded at its upper end into the aperture 76 in the partition 64 and surrounds the connecting rod 75 between the partition 64 and a point normally adjacent the bottom of the float well 74.

A vent opening 86 is provided in a suitable location, such as in the partition 64, for maintaining substantially the same pressure in both the lower condensate chamber 66 and the upper chamber 71, and an appropriately shaped baffle 87 is secured to, or formed integrally with, the partition 64 opposite the steam and condensate inlet 71 for directing condensate entering the inlet downwardly into the condensate chamber outside of the float 72.

Under normal operation, there is sufficient water in the condensate collecting chamber 66 to support the float 72 in its uppermost position shown in Fig. 11. As additional condensate collects in the chamber 66, the water level rises therein and overflows into the float 72. When the level in the float 72 rises to the approximate height indicated by the arrow C in the Fig. 12, the float sinks and actuates the valve lever 25 to open the discharge valve in substantially the manner previously described. By reason of the small size of the vent 86, the pressure tends to drop more rapidly in the upper chamber 67 than in the condensate chamber 66, and the water in the float is forced upwardly through the tube 84, filling the upper chamber 67 and discharging through the outlet 6 until the level in the lower chamber drops to the upper rim of the float and the level within the float approaches the lower end of the tube 84. Reduction of the quantity of liquid in the float increases its buoyancy and, before the liquid level therein drops as far as the lower end of the tube 84, the float reaches its uppermost position again, closing the discharge valve in the process, and completing the cycle of operation.

From the foregoing description of the construction and mode of operation of two embodiments of my invention, it should be apparent that a trap has been provided that is more positive in its operation than the prior art devices. Also, the novel valve lever and its supporting structure permit the application of the general type of dual fulcrum arrangement shown in the above mentioned Kaye patent to a downwardly opening valve, thereby increasing the space available in the housing for accommodating a float of maximum diameter.

The location of the primary fulcrum with re-

spect to the valve seat increases the effective opening of the discharge valve obtainable from a given angular movement of the lever and from given lever arm proportions. This in turn permits the primary fulcrum to be located closer to the spherical center of the valve element, with the result that a greater valve opening force can be derived from a given total lever length and distance of float or bucket travel. These combined effects materially reduce the width and depth of the housing required to meet specific pressure and volume demands. The variable vent mechanism for the inverted bucket and the lost motion effect in the connector 36, together with the provision for rotating the valve element on its valve seat through a small angle before cracking the valve open, substantially increase the effective power obtainable from a bucket of a given diameter and contribute further to the ultimate objectives set forth herein.

The maximum pressure and volume capacities of a given mechanism, as a practical matter, are dependent upon the available space within the trap housing, and there are definite practical and economic limitations upon the trap sizes that may be employed in particular installations and upon the number of trap sizes that may be economically manufactured and stocked to meet the entire range of service demands. Accordingly, the above described advantages of my invention are of great practical significance in raising the maximum limits and extending the range of pressure and volume capacities that can be attained with a single size of trap housing. As a result, the number of sizes of traps that must be stocked to meet all service conditions encountered in practice has been materially reduced.

Having described the invention in detail, I claim:

1. A fluid trap having a housing defining an outlet orifice, a valve seat surrounding said orifice, a valve element having a spherical surface for engaging said seat to close said orifice and for rotating on said seat to and from a normal orifice closing position, a valve actuating lever attached to the valve element and mounted for oscillation to move the valve element in orifice opening and orifice closing directions, said lever being shaped to provide a pair of rocking fulcrum elements spaced apart generally longitudinally of the lever, structure fixed with respect to said orifice and shaped to provide a cooperating pair of stationary fulcrum elements spaced apart generally longitudinally of the lever, said stationary fulcrum elements and said valve seat being arranged in a spacial relationship with said spherical surface and said rocking fulcrum elements such that said rocking fulcrum elements are spaced away from said stationary fulcrum elements when the valve element is in its normal orifice closing position and such that said rocking fulcrum elements successively engage said stationary fulcrum elements, respectively, to provide lever arms of different effective lengths as the lever is moved in an orifice opening direction for first rocking the valve element on the valve seat and then moving the valve element away from the valve seat, and power means disposed in said housing for reciprocation along a path between predetermined limits, said power means being connected to said lever for oscillating the same to move said valve element in orifice opening and orifice closing directions, said valve element being in its normal orifice closing position

when said power means is at one of the limits of its path of travel, whereby movement of the power means along said path for effecting orifice opening movement of the lever first causes the valve element to rotate on its seat for engaging one of said rocking fulcrum elements with one of said stationary fulcrum elements and then causes the lever to rock on said stationary fulcrum elements successively for moving the valve element away from its seat.

2. A fluid trap according to claim 1 in which said structure providing said pair of stationary fulcrum elements is a bifurcated bracket having its two legs straddling said lever and shaped to form a pair of cooperating members on opposite sides of said lever that constitute one of said stationary fulcrum elements and a second pair of cooperating members on opposite sides of said lever that constitute the other of said stationary fulcrum elements.

3. A fluid trap according to claim 1 in which said structure providing said pair of stationary fulcrum elements is a bifurcated bracket having its two legs straddling said lever and shaped to form a pair of cooperating members on opposite sides of said lever that constitute one of said stationary fulcrum elements and a second pair of cooperating members on opposite sides of said lever that constitute the other of said stationary fulcrum elements, and said lever having trunnions extending laterally thereof in opposite directions, said trunnions being shaped to form a pair of cooperating members on opposite sides of said lever that constitute one of said rocking fulcrum elements and a second pair of cooperating members that constitute the other of said rocking fulcrum elements.

4. The device of claim 1 in which the structure providing the pair of stationary fulcrum elements comprises a bifurcated bracket and the lever is mounted between the two spaced legs of the bracket, the two legs of said bracket having aligned apertures therethrough, each of said stationary fulcrum elements being defined by aligned portions of the edges of said apertures, and said lever having trunnions extending laterally thereof in opposite directions into said apertures respectively and forming aligned portions of each of said rocking fulcrum elements for supporting the lever on said stationary fulcrum elements.

5. In a fluid trap having a housing defining an outlet orifice, a valve seat surrounding said orifice, a valve element having a spherical surface for engaging said seat to close said orifice, a valve actuating lever attached to the valve element, structure providing fixed primary and secondary fulcrums upon which the lever successively rocks when actuated to move the valve element away from its seat, said fulcrums being spaced apart generally longitudinally of the lever to provide lever arms of different effective lengths, and power means adapted to move along a path between predetermined limits for rocking the lever about said primary and secondary fulcrums successively to move the valve element away from said orifice, the axis of the primary fulcrum being disposed in a diametric plane of the spherical surface of said valve element and said plane being substantially parallel to said seat at a stage during rocking of the lever on the primary fulcrum.

6. In a fluid trap having a housing defining a liquid and vapor receiving chamber and an outlet orifice that provides an interior valve seat, a valve element within the chamber having a

spherical surface normally engaging said seat, a valve actuating lever attached to said valve element and providing primary and secondary fulcrum edges thereon spaced apart longitudinally thereof, structure providing fixed fulcrum bearing surfaces for said fulcrum edges, and power means adapted to reciprocate along a path between predetermined limits for rocking said lever on said primary and secondary fulcrum edges successively to move the valve element away from said seat, the axis of the primary fulcrum being disposed in a diametric plane of the spherical surface of said valve element, and said plane being substantially parallel to said seat at a stage during rocking of the valve element on the primary fulcrum.

7. In a fluid trap having a housing defining a liquid and vapor receiving chamber and an outlet orifice that provides an interior valve seat, a valve element within the chamber having a spherical surface normally engaging said seat, a valve actuating lever attached to said valve element and providing primary and secondary fulcrum edges thereon spaced apart longitudinally thereof, structure providing fixed fulcrum bearing surfaces for said fulcrum edges, and power means adapted to move along a path between predetermined limits for rocking said lever on said primary and secondary fulcrum edges successively to move the valve element away from said seat, the axis of the primary fulcrum being disposed in a diametric plane of the spherical surface of said valve element and at a distance from the spherical center of said surface less than its radius of curvature, and said plane being substantially parallel to said seat at a stage during rocking of the lever on the primary fulcrum.

8. In a fluid trap having a housing defining a liquid and vapor receiving chamber and an outlet orifice that provides a circular interior valve seat, a valve element within the chamber having a spherical surface normally engaging said seat for closing said orifice, a valve actuating lever attached to said valve element and providing primary and secondary pairs of aligned fulcrum edges thereon, the fulcrum edges of each pair extending transversely of the lever beyond opposite sides of said valve element, the pair of secondary fulcrum edges being spaced from the pair of primary fulcrum edges longitudinally of said lever and at a greater distance from the valve element, structure that is fixed with respect to said seat providing bearing surfaces for said pairs of fulcrum edges and power means adapted to move along a path between predetermined limits for rocking the lever about said primary and secondary fulcrum edges successively to move the valve element away from its seat, the pair of primary fulcrum edges being operative during initial movement of the valve element away from its seat and being disposed in a diametric plane of the spherical surface of said valve, and said diametric plane being substantially parallel to said seat at a stage during the time the pair of primary fulcrum edges engages its bearing surfaces.

9. In a fluid trap having a housing defining a liquid and vapor receiving chamber and an outlet orifice that provides a circular interior valve seat, a valve element within the chamber having a spherical surface normally engaging said seat, a valve actuating lever attached to said valve element and providing two pairs of fulcrum edges thereon, the fulcrum edges of each pair

being aligned and extending laterally beyond opposite sides of said valve element and the pairs of fulcrum edges being spaced longitudinally of said lever, structure that is fixed with respect to said seat providing bearing surfaces for said fulcrum edges, and power means adapted to move along a path between predetermined limits for rocking said lever on said pairs of fulcrum edges successively for moving the valve element away from its seat, the pair of said fulcrum edges about which said lever first rocks being disposed in a diametric plane of the spherical surface of said valve and on a line at a distance from the spherical center of said surface less than its radius of curvature, and said plane being substantially parallel to said seat at a stage during the time said lever is rocking on the first pair of fulcrum edges, and the other pair of said fulcrum edges being disposed at a greater distance from said spherical center.

10. In a fluid trap having a housing defining a liquid and vapor receiving chamber, an inlet opening at the bottom of the chamber, an outlet orifice, a valve element for opening and closing the outlet orifice, a lever for moving said valve element, and a float of the inverted bucket type suspended from said lever over said inlet opening for actuating said lever to open and close the outlet orifice, the combination therewith of a variable vent and connector mechanism for suspending the bucket from the lever, said mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction.

11. The improvement according to claim 10 in which said spring is disposed inside said bucket and engages the stem therein.

12. The improvement according to claim 10 in which said spring is mounted on said stem inside the bucket and engages the inner surface of the bucket.

13. The improvement according to claim 10 in which said spring is a leaf spring mounted at its center on said stem inside the bucket, said spring being shaped to bear upwardly at its opposite ends against the inside of the bucket and downwardly at its center against its connection with said stem.

14. A fluid trap according to claim 1 in which the fulcrum axis about which the lever arm first rocks during movement of the valve element away from its seat is disposed in a diametric plane of the spherical surface of the valve element, said plane being substantially parallel to said seat at a stage during rotation of said lever about said axis.

15. A fluid trap according to claim 1 in which the fulcrum axis about which the lever arm first rocks during movement of the valve element away from its seat is disposed in a diametric plane of the spherical surface of the valve element, said

plane being substantially parallel to said seat at a stage during rotation of said lever about said axis, and in which said axis is disposed at a distance from the spherical center of said surface less than its radius of curvature.

16. A fluid trap according to claim 1 in which said power means is a float of the inverted bucket type suspended from said lever by a variable vent and connector mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction.

17. A fluid trap according to claim 1 in which said power means is a float of the inverted bucket type suspended from said lever by a variable vent and connector mechanism comprising a vertically disposed stem carrying the weight of the bucket, said stem being pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction, said spring being mounted on said stem inside the bucket for engaging the inner surface of the bucket.

18. A fluid trap according to claim 1 in which said power means is a float of the inverted bucket type suspended from said lever by a variable vent and connector mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and yieldable means associated therewith for urging the intermediate portion of said stem downwardly against the top of the bucket under conditions of maximum buoyancy of the bucket and to yield against a force less than that required to move the lever in an orifice opening direction, said yieldable means comprising a leaf spring mounted at its center on said stem inside the bucket, said spring being shaped to bear upwardly at its opposite ends against the inside of the bucket and downwardly at its center against its connection with said stem.

19. A fluid trap according to claim 5 in which said power means is a float of the inverted bucket type suspended from said lever by a variable vent and connector mechanism comprising a ver-

tically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction.

20. A fluid trap according to claim 5 in which said power means is a float of the inverted bucket type suspended from said lever by a variable vent and connector mechanism comprising a vertically disposed stem carrying the weight of the bucket, said stem being pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction, said spring being mounted on said stem inside the bucket for engaging the inner surface of the bucket.

21. A fluid trap according to claim 5 in which said power means is a float of the inverted bucket type suspended from said lever by a variable vent and connector mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and yieldable means associated therewith for urging the intermediate portion of said stem downwardly against the top of the bucket, said yieldable means being selected to hold the intermediate portion of said stem downwardly against the top of the bucket under conditions of maximum buoyancy of the bucket and to yield against a force less than that required to move the lever in an orifice opening direction, said yieldable means comprising a leaf spring mounted at its center on said stem inside the bucket, said spring being shaped to bear upwardly at its opposite ends against the inside of the bucket and downwardly at its center against its connection with said stem.

22. A fluid trap according to claim 1 in which the fulcrum axis about which the lever arm first rocks during movement of the valve element away from its seat is disposed in a diametric plane of the spherical surface of the valve element, said plane being substantially parallel to said seat at a stage during rotation of said lever about said axis, and in which said power means is a float

of the inverted bucket type suspended from said lever by a variable vent and connector mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction.

23. A fluid trap according to claim 1 in which the fulcrum axis about which the lever arm first rocks during movement of the valve element away from its seat is disposed in a diametric plane of the spherical surface of the valve element, said plane being substantially parallel to said seat at a stage during rotation of said lever about said axis, and in which said power means is a float of the inverted bucket type suspended from said lever by a variable vent and connector mechanism comprising a vertically disposed stem carrying the weight of the bucket, said stem being pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and a spring associated therewith for urging the intermediate portion of said stem downwardly against the top of the bucket, the stiffness of said spring being selected to hold the intermediate portion of said stem downwardly against the top of the bucket under conditions of maximum buoyancy of the bucket and to yield against a force less than that required to move the lever in an orifice opening direction, said spring being mounted on said stem inside the bucket for engaging the inner surface of the bucket.

24. A fluid trap according to claim 1 in which the fulcrum axis about which the lever arm first rocks during movement of the valve element away from its seat is disposed in a diametric plane of the spherical surface of the valve element, said plane being substantially parallel to said seat at a stage during rotation of said lever about said axis, and in which said power means is a float of the inverted bucket type suspended from said lever by a variable vent and connector mechanism comprising a vertically disposed stem pivotally connected at its upper end to the lever and having its lower end projecting with substantial clearance through an aperture centrally disposed in the top of the bucket, said stem including an enlarged intermediate portion adapted to seat downwardly against the top of the bucket and completely close said aperture, and yieldable means associated therewith for urging the intermediate portion of said stem downwardly against the top of the bucket, said yieldable means being selected to hold the intermediate portion of said stem downwardly against the top of the bucket under conditions of maximum buoyancy of the bucket and to yield against a force less than that required to move the lever

in an orifice opening direction, said yieldable means comprising a leaf spring mounted at its center on said stem inside the bucket, said spring being shaped to bear upwardly at its opposite ends against the inside of the bucket and downwardly at its center against its connection with said stem.

25. The device of claim 1 including an abutment on the structure providing said stationary fulcrum elements disposed to engage said lever and limit its rocking movement in a valve closing direction when the valve element is in its normal closed position.

26. The device of claim 1 in which the structure providing the pair of stationary fulcrum elements comprises a bifurcated bracket and the lever is mounted between the two spaced legs of the bracket, the two legs of said bracket having aligned apertures therethrough, each of said stationary fulcrum elements being defined by 15 aligned portions of the edges of said apertures,

5 and said lever having trunnions extending laterally thereof in opposite directions into said apertures respectively and forming aligned portions of each of said rocking fulcrum elements for supporting the lever on said stationary fulcrum elements, the edges of said apertures also providing abutments disposed to engage said lever and limit its rocking movement in a valve closing direction when the valve element is in its normal closed position.
